BETHEL ABIEL REVELLI, OF TURIN, ITALY

AUTOMATIC RIFLE

Application filed October 18, 1929, Serial No. 400,639, and in Italy October 31, 1928.

The automatic rifle which is intended to replace before long the ordinary rifle cannot have a mechanism similar to that of machine guns or machine rifles which are distributed to companies of specialized gunners. Its weight should not reasonably exceed that of the ordinary rifle (4 kgs.) otherwise the soldier is unable to carry the necessary ammunition; moreover the weapon should be easily handled, used, dismounted and readily mounted like the rifles now in use and be provided with a non-automatic firing means for use in case the automatic mechanism is damaged. In this case the gunner uses the weapon like an ordinary rifle opening and closing the breech bolt and handling the rifle by movements well known to him through long experience. When the mechanism is arranged for automatic working, the shots are fired much more rapidly and easily and without effort, as advisable in attacks or sudden defense for physiological reasons.

The automatic rifle according to this invention satisfies all the requirements mentioned above.

The accompanying drawings show a constructional form of my improved rifle—

Figure 1 is a vertical longitudinal section.

Figure 2 is a cross section on line A—A of Figure 1.

Figure 3 shows the device for transforming the automatic rifle into an ordinary rifle.

Figure 4 is a partial side view.

Figure 5 is a vertical cross section on line B—B of Figure 4.

The rifle has a recoiling barrel and is of the same weight and size as an ordinary rifle.

1 denotes the butt; 2 the breech, 3 the breech bolt, 4 the striker and 5 the barrel.

40 The automatic closure of the breech bolt 3 is obtained by means of the teeth 3a on the head of the breech bolt, which by a slight rotation are caused to engage against ribs 5a provided on the inner surface of a short

45 rear extension of the barrel 5 recoiling with this latter by a short extent while the breech remains stationary and is brought forward again by a suitable spiral spring 6.

50 The device for rotating the breech bolt to the closed position comprises a short cylin-

drical coil spring 12 interposed between the front portion of the striker 4 and the bottom of the breech bolt 3. The end turns of the spring 12 are bent over longitudinally and introduced into a corresponding hole bored 55 in the striker and breech bolt respectively.

The spring 12 works under torque stress and as it is mounted under a certain load it tends to rotate the breech bolt 3 with respect to the striker 4. As this latter is guided 60 in a rectilinear direction in the breech by a tooth 4a movable in a longitudinal groove 2a on the breech, the breech bolt tends to rotate towards its closed position, this rotation taking place at the end of its forward 65 stroke as soon as its tooth 3a is disengaged from the rectilinear guide groove 2c.

It is obvious that the load on the spring 12 is easily adjustable in order to ensure the closure of the breech bolt.

70 The striking mechanism comprises a cock 18 provided with a resilient tooth 25 capable of longitudinal movement and adapted to engage with the lower face of a stationary cross-piece 26 of the breech 2 for holding the cock 18 in cocked position when it is tilted backwards.

75 The trigger 20 is pivoted at 21 to the bridge-piece 15 so that by pulling it backwardly it pushes forward by its upper arm a lever 22 80 pivoted to the trigger in 23. The lever 22 thus abuts the resilient tooth 25 of the cock and pushes it forward, until it is disengaged from the cross-piece 26 thus setting free the cock which rotates forward snapping against 85 the striker 4.

As it is well known the breech bolt recoils so quickly that the cock is tilted backwards and tends to assume its cocked position before the gunner has time to release the trigger, so that the lever 22 is still in its forward position and the cock remains in cocked position on account of the fact that its resilient tooth 25 abuts under the rod 22. As soon as 90 the gunner releases the trigger, the lever 22 slides backwards between the cross-piece 26 and the tooth 25 until this latter is set free from the lever and abuts under the cross-piece. This takes place successively as the 95 100

trigger is pressed upon by the finger and then released.

A strong coil spring 27 causes the cock 18 to hit the striker.

5 The cock 18 is provided on top with a side rib 18a ensuring the complete rotation of the cock (Figs. 1 and 2) and preventing it to come in front of the breech bolt upon accidental snapping of the trigger when the breech bolt is in its rearward position.

10 When the breech 2 is detached from the magazine by removing the two screws 16 which connect both parts exactly as in the Italian rifle Model 91, the magazine and cock 15 remain connected together and the mechanism is easily inspected.

15 The device for automatically opening the breech bolt on firing is shown in Figure 4. It consists of a disk or roller 13 pivoted to 20 the stationary breech 2, that advantageously replaces the usual inclined surfaces adopted in the first automatic fire arms no longer in use. The inclined surface always causes a considerable friction which hinders the free 25 rotation of the breech bolt and when lubrication fails temporarily stops it, so that after rotation of the breech bolt the gas pressure in the barrel has already completely vanished and recoil does not take place or is insufficient.

30 The disk or roller 13 according to this invention enables the slipper 3b of the breech bolt to slide with rolling instead of with sliding friction and the above mentioned disadvantages are completely obviated. The 35 displacement of the tooth takes place during the short recoil stroke of the barrel and causes the breech bolt to rotate with respect to the barrel and to become disengaged. The breech bolt then recoils further guided by the slipper 40 3b that slides in the groove 2a, ejecting the case of the cartridge that has been fired; in the next forward stroke of the breech bolt a fresh cartridge is pushed into the cartridge chamber whereupon the breech bolt rotates 45 to its closed position under the action of the spring 12.

Figure 3 shows the device for transforming the automatic fire arm into an ordinary rifle. The said device comprises a ring 113 with 50 peripheral teeth 113a rotatably mounted on the barrel and kept against rotation with respect to this latter. The ring 113 can be rotated through a limited angle by means of an outer milled button not shown for 55 simplicity sake. The breech 2 or preferably its extension 7 is provided with an equal number of teeth 7a opposite the teeth 113a.

When the ring 113 is rotated by such an extent that its teeth come against the breech 30 teeth 7a, the barrel cannot recoil with respect to the breech and the automatic opening of the breech bolt does not take place as the slipper 3b of the breech bolt does not contact with the rotatable disc 13, while when 35 the ring 113 is rotated in such manner that

its teeth come opposite the recesses between the teeth 7a on the breech or on its extension 7, the barrel recoils and the fire arm is opened and works automatically.

Two reference letters, e. g., A and R on the 70 ring clearly denote whether the firearm is arranged for automatic or non-automatic firing.

Figure 1 shows the "safety" device constituted by an oscillating lever 30 operable by 75 acting upon its lower edge. When this latter is forward the lever holds the cock 18 fixed in a rearward position such that the resilient tooth 25 of the cock does not bear on the cross-piece 26 of the breech by virtue of the two 80 positions of the safety lever 30 and the right-hand projection of the cock respectively, said positions being such that in order to place the fire arm in the safety position, the cock must be rotated through an angle slightly wider 85 than that required for the cocked position.

Should the gunner pull the trigger by inadvertence when the fire arm is in the safety position, the resilient tooth 25 is withdrawn 90 into the cock, this latter being always held stationary under the action of the lever 30. The gunner is thereby made aware that he must place the weapon out of the safety position by pulling back the outer edge of the lever 30 which he easily effects by his right 95 hand when the fire arm rests on the shoulder.

The rifle works as follows:

Supposing the ring shown in Fig. 3 is arranged for automatic firing, and the fire arm 100 is not in the safety position, the gunner loads the weapon by means of a loader which is introduced from underneath like the loader of an ordinary automatic pistol, the said loader containing from five to ten cartridges, or even more, arranged in one or in two parallel rows as in Lee's rifle.

By introducing the loader from underneath the hole through which the cartridge cases are ejected is advantageously made inclined to the right (or to the left) and not upwards; the cartridge cases are ejected laterally without disturbing the gunner; moreover when the explosion gases escape owing to imperfect construction of the cartridges or other disturbance they cannot injure the gunner. A bore of limited size for ejecting the cartridge cases has the further advantage of permitting a better protection of the fire arm against rain, dust and mud and of 115 strengthening the breech.

The further operations are the following: The gunner opens the breech bolt 3 rotating it by means of the handle 14, without any effort for overcoming the recoil of the barrel, 120 next he introduces a cartridge into the barrel by filling it in with his hand or letting the handle free to move forward—he then pulls the trigger and fires.

The barrel 5 recoils by a short extent, the 125 slipper 3b of the breech bolt abuts and slides

on the ring 13 which is caused to turn, the breech bolt 3 rotates, opens, recoils, ejects the cartridge case, next moves forward under the action of the return spring 11, pushes a 5 fresh cartridge into the chamber and remains closed.

These opening operations are effected most rapidly while the trigger is still being pulled backwardly by the gunner. The rod 10 22 hinged above to the trigger is still forward, the resilient tooth 25 of the cock 18 abutting under the said rod. By releasing the trigger, the rod withdraws and the resilient tooth 25 of the cock abuts under the 15 cross-piece 26 of the breech.

The parts are now again in the initial position and the next shots are fired by intermittently pulling the trigger so long as there are 20 cartridges in the magazine. About 50 shots can be fired in one minute.

When cartridges of the usual type are employed, the firearm is used as an ordinary rifle.

Normally the firearm is dismounted by 25 screwing the rear plug 8 and pulling back the breech bolt with its striker. In emergency cases the front and rear screws 16 connecting the magazine with the stationary breech are removed.

30 It is well understood that the form and constructional details of the weapon may be varied from the construction which has been described and illustrated by way of example without departing from the spirit of this 35 invention.

What I claim is:

1. An automatic rifle comprising a stationary breech, a barrel at one end of the breech, interengaged toothed connections between

40 the barrel and a slidable breech bolt within the breech, a striker slidably mounted in the breech bolt, a coiled spring connection between the striker and the breech bolt and forming means whereby the interengaged

45 toothed connections between the breech bolt and barrel is maintained and means cooperating with the breech bolt on its rearward movement whereby the barrel will move rearwardly a limited distance, the breech bolt rotated, the toothed engagement disconnected and spring means whereby said striker and

50 breech bolt will be forced to closed position with the toothed engagement between the breech bolt and barrel.

55 2. The combination with an automatic rifle comprising a stationary breech, a breech bolt slidably mounted in the breech, a barrel slidably mounted in the breech, interengaged toothed connection between the breech bolt

60 and the barrel and circular rotatable means cooperating with the breech bolt, whereby upon rearward movement of the barrel, said toothed connection will cause the breech bolt to move rearwardly, then disengage from the

after a partial rotation for the disengaging operation and spring means cooperating with the breech bolt, whereby it will again be moved into toothed interengagement with the barrel.

3. The combination with an automatic rifle comprising a stationary breech, a breech bolt slidably mounted in the breech, a barrel slidably mounted in the breech, a striker slidably mounted in the breech bolt, toothed interengagement between the barrel and breech bolt, circular rotatable means whereby upon rearward movement of the breech bolt and barrel in toothed interengagement, said toothed interengagement will be disconnected and the breech bolt will move rearwardly and torque spring means cooperating with the breech bolt whereby upon its forward movement it will resume its toothed interengagement with the barrel and will partially rotate 85 into locked toothed interengagement with the barrel.

4. The combination with a sliding bolt of an automatic gun, said bolt having a toothed interengagement with a slid able barrel, of a 90 striker slidably mounted in the bolt, a shoulder carried by said striker and extending into a stationary elongated slot for preventing rotation of the striker, a coiled spring carried by the striker within the bolt, one end of the 95 coiled spring being anchored to the striker and the other end to the bolt and cam means cooperating with the bolt whereby upon rearward movement thereof the toothed engagement with the barrel will be disconnected, the coiled spring tensioned and spring means cooperating with the striker for normally forcing the same forwardly.

5. The combination with an automatic gun having a slid able breech bolt partially rotatable against spring action in its rearward movement, of an arm carried by the breech bolt and extending outwardly therefrom in the plane below a guide groove, and an anti-frictional roller in the path of said arm and 105 positioned whereby upon rearward movement of the breech bolt said arm will be forced into position where it will enter the guide groove.

6. In combination with an automatic rifle, 110 a breech bolt movable forwardly and rearwardly for automatically loading and unloading said rifle, a revolvable projection cooperable with said breech bolt by rolling friction, whereby the breech bolt is rotated upon its rearward movement, a torque spring operatively connected to said breech bolt, whereby upon its forward movement the breech bolt is rotated in a direction opposite to the first named rotation.

In testimony that I claim the foregoing as my invention, I have signed my name.

BETHEL ABIEL REVELLI.
